SPOON OR SIMILAR ARTICLE

Felix A. Mirando, Jr., Providence, R. I., assignor to Imperial Knife Company, Inc., New York, N. Y., a corporation of Rhode Island

Application November 15, 1955, Serial No. 38,901

Term of patent 14 years

(Cl. D54—12)

Fig. 1 is a top view of a spoon showing my new design; and

Figs. 2 and 3 are side and bottom views, respectively, of said spoon.

The dominant features of the invention reside in the portions shown in full lines.

I claim:

The ornamental design for a spoon or similar article, substantially as shown, and described.
